UNITED STATES PATENT OFFICE.

JAMES MACLEOD, OF GLASGOW, SCOTLAND, ASSIGNOR OF ONE-HALF TO HUGH REID,
OF GLASGOW, SCOTLAND.

AIR-COOLED OR EVAPORATIVE SURFACE CONDENSER.

1,427,159.

Specification of Letters Patent. Patented Aug. 29, 1922.

Application filed February 28, 1921. Serial No. 448,700.

To all whom it may concern:

Be it known that I, JAMES MACLEOD, a subject of the King of the United Kingdom of Great Britain and Ireland, and residing at Glasgow, Scotland, have invented a certain new and useful Improvement in Air-Cooled or Evaporative Surface Condensers, of which the following is a specification.

This invention relates to air-cooled or evaporative surface condensers.

The invention consists in a condenser having surface heat-exchanging elements or tubes in groups, the tubes of the different groups being so arranged that the tube rows of any given group come intermediate the tube rows of an adjacent group, thereby ensuring a uniform temperature rise of the cooling medium and ensuring an equal and uniform distribution of the evaporative liquid over the condenser surface in fine layers, if such evaporative liquid be employed.

Referring to the drawings Fig. 1 is an end elevation; Fig. 2 is a sectional elevation 25 of the condenser on the line 2--2 of Fig. 1; Fig. 3 is a transverse section of the cooling tubes or heat-exchanging elements; Fig. 4 is a detail, broken out longitudinal section 30 of the cooling tubes; Fig. 5 shows a modification of the arrangement shown in Fig. 3; and Fig. 6 is a diagram illustrating an installation hereinafter referred to.

Referring to Figs. 1 and 2, the steam enters the condenser through the pipe A into 35 the upper header B; and passes downwards through the group of tubes or heat-exchanging elements C into the lower header D and thence upwards through the group of tubes or heat-exchanging elements E into the 40 upper header B, and thence downwards through the tubes or heat-exchanging elements G into the bottom header D. The condensate resulting from the passage of steam through the tubes C and E may be withdrawn at F; the condensate resulting from 45 the passage of steam through the tubes G may be withdrawn at K. As shown, the headers B and D are each divided into two sections by means of partitions L and M, 50 the condenser being constructed according to the three flow system.

Inspection doors are fitted to the headers at O, P, Q, R.

The tubes are preferably divided into ten 55 rows forming three distinct groups C, E and

G; the first group comprising five rows; the second group three rows and the third group two rows; thereby the steam velocities inside the tubes due to decreased volume are maintained practically constant. The steam 60 passes through the tubes S (Figs. 3 and 5) and the gaseous cooling medium (air) passes through the spaces T between the tube rows, each alternate tube group being pitched so that the rows of tubes in this group are in 65 planes intermediate the planes of the rows of the preceding group, each row of tubes in one group, thus splitting the core of the gaseous cooling medium coming from between the rows of the preceding group, and 70 ensuring a uniform rise in the temperature of the air during its passage through the condenser. The cooling medium is drawn through the condenser over the tube surfaces by means of a suction fan appliance U propelled by an electrical motor V (Fig. 2). Liquid is supplied to sprayers W (Fig. 1) 75 through the pipes a. The liquid is sprayed in front of the condenser, and is carried through by the gaseous cooling medium and 80 deposited on the outer tube surfaces and evaporated due to the heat of the vapour inside the tubes, the liquid thus evaporated being carried rapidly away by the gaseous cooling medium. Similar sprayers are also 85 fitted in the spaces b and c (Fig. 2) so that each group of tubes is provided with an independent supply of liquid in the form of a fine spray which also ensures that all the tubes throughout the condenser will be 90 covered with a thin film or layer of liquid.

The condenser is so constructed that the air during its passage between the tubes of each group becomes heated and in this state absorbs the vapour generated by the films 95 of liquid in contact with the outer tube surfaces. The air entering the condenser and passing between the tube surfaces through the group of tubes G (Fig. 2) becomes heated, and, in entering the space b, it is brought 100 into contact with a fresh supply of cold liquid in a fine spray, the effect being to cool the air and partially to condense the vapour before entering the group of tubes E, when it is again heated and again comes into 105 contact with a further fresh supply of liquid at c, being again cooled before entering the group of tubes C; this condition may be continued for any number of groups.

The tubes or heat-exchanging elements S 110

are preferably expanded into the bottom tube plate and secured to the top tube plate by means of packing and ferrules (Fig. 4).

In the installation shown in Fig. 6 in which the heat-exchanging elements 1 of the condenser are in a horizontal position, the steam enters at 2 and passes through the tubes in a single flow, the condensate being withdrawn at 3 from the header 4, the non-condensable gases being withdrawn at a point near the upper end of the header 4; evaporative liquid being sprayed at the points 5 at the entrance of the condenser surface and withdrawn along with the air by a fan 6. The pocket 7 formed on the header serves to collect the condensate and prevent flooding.

Figs. 3 and 5 show how the rows of tubes in one group are staggered, or arranged in different planes, with relation to the rows of tubes of an adjacent group, and Fig. 5 also shows a staggered arrangement of the tubes of each group.

I claim:—

1. A condenser having surface heat-exchanging tubes or elements in groups, the rows of tubes or elements of each group being staggered with relation to the rows of elements of an adjacent group, means for passing a cooling medium successively over the tubes or elements of said groups, and means for spraying evaporative liquid on the elements of the first group traversed by the cooling medium.

2. A condenser comprising surface heat-exchanging tubes or elements arranged in groups, the rows of tubes or elements in the different groups being staggered with relation to the rows of tubes or elements of an adjacent group, hollow headers into which both ends of said tubes or elements open, one of said headers being constructed for the drainage of the condensate, and means for spraying a cooling liquid on said condensing tubes or elements. 35

3. A condenser comprising surface heat-exchanging tubes or elements arranged in groups, the rows of tubes or elements in the different groups being staggered with relation to the rows of tubes or elements of an adjacent group, hollow headers into which both ends of said tubes or elements open, said headers being provided with partitions to cause a reverse flow of the fluid in adjacent groups of heat-exchanging or condensing tubes or elements, one of said headers being constructed for the drainage of the condensate, and means for spraying a cooling liquid on said condensing tubes or elements. 40 45 50 55

In testimony whereof I have signed my name to this specification in the presence of two subscribing witnesses.

JAMES MACLEOD.
